HAGEN, K, DENMARK.

MACHINE FOR GRINDING SHAVING-MACHINE BLADES.

1,393,634.

Specification of Letters Patent.

Patented Oct. 11, 1921.

Application filed August 1, 1918. Serial No. 247,895.

To all whom it may concern:

Be it known that we, MORTEN WILHELM MØLLER, engineer, and ALBERT EJNAR HARMS, wholesale merchant, residing at Copenhagen, No 11 Frederhsgade, Denmark, have invented certain new and useful Improvements in Machines for Grinding Shaving-Machine Blades, of which the following is a specification.

10 The object of the present invention is to provide a machine for grinding the blades of safety razors. The machine is of the type wherein two grinding rollers are provided, which rotate first in one direction and then in the other, and wherein a blade holder is arranged between the rollers whereby the four sides of the two edges of the blade are sharpened.

Experience has shown that the grinding of all four sides exactly alike is attained with difficulty, and the object of the present invention is therefore to produce a machine which automatically executes the reversal of the blade after the conclusion of each grinding period in one direction in such a manner that each grinding period is controlled, thereby insuring that the grinding periods in each direction of rotation of the grinding wheels are of exactly the same duration; or in other words, the length of grinding surface which operates upon the blade is the same during the rotation of the rollers in each direction.

The invention is shown in the accompanying drawing, in which:

Figure 1 shows the front view of the machine with the front plate removed.

Fig. 2 is a section taken on the line II--II of Fig. 1.

40 Fig. 3 shows a detail of the blade holder in longitudinal section.

Fig. 4 is an end elevational detail of the blade holder.

Fig. 5 is a longitudinal section of the blade holder on a plane at right angles to Fig. 3.

45 Fig. 6 is a front view of a modified form with the front plates removed.

In carrying out the invention according to one mode, the machine consists of a motion transmitting mechanism, inclosed between plates 3 and 4, for two grinding rollers 7 and 8, together with a reversible blade holder

(not shown in the drawings) carried by the spindle 9.

The two grinding rollers 7 and 8 are 55 mounted on pivots 1 and 2, fitted with gear wheels 5 and 6 co-operating with a toothed rack element in the form of a toothed segment 11, the nave 18 of which is provided with a handle D and is rotatable about a 60 pivot 12.

By operating the toothed segment 11 alternately in the one and in the other direction, the two grinding rollers will rotate alternately counter-clockwise and clockwise. 65

The blade holder consists of a cylinder or the like 22, provided with two slots and mounted on a pivot 9 with gear wheel 10. The blade A is placed between two cheeks 24, which may have studs 25 corresponding to 70 holes, if any, in the blade A and this together with the two cheeks 24 may now slide down in the cylinder, so that the two edges of the blade protrude through the slots 23.

Two blade springs 20 and 21 are provided 75 to control the oscillation of the lever 16 and to restore it to its normal position.

The apparatus operates as follows:—

When the handle D is moved alternately to one side or the other, the two grinding 80 rollers 7 and 8 will be caused to rotate in a manner previously explained. At the same time the cam 19 will engage the tip of the lever 16 and push it aside, (Fig. 1 shows in dotted lines one of the two positions which 85 the lever occupies when acted upon by the cam), and this movement will be transmitted to the swing arm 13, so that the toothed part thereof will cause the gear wheel 10 to rotate, thereby turning the blade holder 9 90 over, so that its position is reversed and the other two sides of the cutting edges of the blade A will be pressed against the grinding rollers.

When the toothed segment has reached the 95 end of its movement in one direction, the tip of the lever 16 will be free of the cam 19, when, by virtue of the elasticity of the blade (under its pressure against the grinding rollers) and the action of the two springs 100 20 and 21, it will assume its vertical position, in which the tip of the lever 16 will lie behind the opposite end of the cam.

By moving the toothed segment back in the other direction, by operation of the handle D, the end of the cam will engage the lever 16, canting it over in a direction opposite to that shown in dotted lines in the drawing, whereby the blade holder will be again reversed.

It will be observed that the duration of the period of grinding in each direction is the same, this being controlled in such a manner that the handle D cannot be reversed until its full stroke has been accomplished by reason of the co-operation between the member 16 and the cam 19, the engagement between these two members being such that reversion cannot take place while the tip of the member is upon the curved surface of the cam, but must be permitted to be free thereof and lie in a vertical position at one end or the other of the cam before the handle can be reversed.

In the modification shown in Fig. 6, swing arm 13 is dispensed with. In this form a lever 16' is applied directly on the pivot 9', and is formed with a rounded or suitably shaped end to engage the surface of the cam 19', which may be mounted upon the toothed segment 11' rotatable about pivot 12'. A spring 21' is provided to control the movement of the lever 16' tending to return it to its normal or mid position. A pair of grinding rollers 7', 8' are provided with gear wheels 5' and 6' engaging with toothed segment 11'.

In operating the device according to this form, as the handle D' is moved from left to right of the drawing, the cam 19' engages the lever 16', and causes it to be turned about its pivot 9' into the dotted position shown on the right of the center line, passing through said spindle, so that the end of the lever 16' rests on the surface of the cam 19', permitting the latter to slide beneath it. While in this position, any reversal of the handle will not produce a consequent turning over of the lever, and this will not take place until the latter has slipped down behind the other end of the cam. Upon the reversal of the handle D' at the completion of its stroke, the lever is caused to assume the other position shown. When not engaged by the cam the lever occupies the mid position shown in full lines.

Having now described our invention, what we claim as new and desire to secure by Letters Patent is:—

1. Grinding apparatus for safety razor blades, comprising a frame, a pair of grinding rollers carried by said frame, gear wheels provided on said rollers, a pivoted member comprising a cam member, toothed segment engaging with said gear wheels and an oscillating handle attached to the pivoted member whereby said pivoted member may be

manually oscillated, a blade holder and means adapted to contact with said cam for maintaining the blade in contact with the rollers during their oscillation and for oscillating the blade holder.

2. Grinding apparatus for safety razor blades, comprising a frame, a pair of grinding rollers carried by said frame, gear wheels provided on said rollers, a pivoted member comprising a cam member, a toothed segment engaging with said gear wheels and an oscillating handle attached to the pivoted member whereby said pivoted member may be manually oscillated, a blade holder and a pivoted lever, adapted to be engaged by said cam member for maintaining the blade in contact with the rollers during their oscillation and for oscillating the blade holder.

3. Grinding apparatus for safety razor blades, comprising a frame, a pair of grinding rollers carried by said frame, gear wheels provided on said rollers, a pivoted member comprising a cam member, a toothed segment engaging with said gear wheels and an oscillating handle attached to the pivoted member whereby said pivoted member may be manually oscillated, a blade holder, a pivoted lever operatively connected with said blade holder and resilient means normally holding said pivoted lever with one end in the path of said oscillating cam member, said cam member being of a length to release said pivoted lever at the end of an oscillation of the cam and engage said pivoted lever on a return oscillation to turn the blade into operative contact with the grinding rollers.

4. Grinding apparatus for safety razor blades, comprising a frame, a pair of grinding rollers carried by said frame, gear wheels provided on said rollers, a pivoted member comprising a cam member, a toothed segment engaging with said gear wheels and an oscillating handle attached to the pivoted member whereby said pivoted member may be manually oscillated, a blade holder provided with a gear wheel, a pivoted swing arm having teeth adapted to engage the gear wheel of the blade holder, a pivoted lever one end of which is operatively connected with one end of said pivoted swing arm, and resilient means normally holding the other end of said pivoted lever in the path of said oscillating cam member, said cam member being of a length to release said pivoted lever at the end of an oscillation of the cam and engage said pivoted lever on a return oscillation to turn the blade into operative contact with the grinding roller.

5. Grinding apparatus for safety razor blades comprising a frame, a pair of grinding rollers carried by said frame, gear wheels provided on said rollers, a pivoted

member comprising a cam member, a toothed segment engaging with said gear wheels and an oscillating handle attached to the pivoted member whereby said pivoted member 5 may be manually oscillated, a blade holder, means adapted to contact with said cam for maintaining the blade in contact with the rollers during their oscillation for oscillating the blade holder, and for preventing re-

versal of the rollers before the end of a 10 stroke.

In testimony whereof we affix our signatures in presence of two witnesses.
